UNITED STATES PATENT OFFICE.

JULIUS C. LANDMANN, OF DUTCH FLAT, CALIFORNIA.

WATCH-REGULATOR.

SPECIFICATION forming part of Letters Patent No. 269,588, dated December 26, 1882.

Application filed August 24, 1882. (No model.)

To all whom it may concern:

Be it known that I, JULIUS C. LANDMANN, of Dutch Flat, county of Placer, State of California, have invented an Improved Watch-Regulating Attachment; and I hereby declare the following to be a full, clear, and exact description thereof.

My invention relates to an attachment for regulating the speed of watches; and it consists of a segment-rack attached to the outer end of the regulating-arm. With this meshes a pinion the shaft of which extends through the watch and has another pinion upon the opposite end, which is engaged by the teeth 15 of a gear-wheel, the shaft of which extends through the face and has an index-arm secured to it. By moving this index-arm the regulator is adjusted without opening the watch, a circular scale showing the amount of adjustment made.

Referring to the accompanying drawings for a more complete explanation of my invention, Figure 1 is a view of my watch. Figs. 2, 3, and 4 show the interior construction.

A is a watch having the balance-wheel B, hair-spring C, and the regulator-arm D in the usual position. The arm D is made stronger in my invention than in the ordinary construction, as it has to carry a segment of a circle, 25 E, the periphery of which is formed into a toothed rack, as shown. Through the inner cases of the watch a shaft passes, and has a pinion, G, fixed upon one end, so as to mesh or engage with the rack E. The other end of 30 the shaft has another pinion, H, which engages a gear-wheel, I, upon the outside of the inner

case, opposite to the regulator. The shaft of this wheel passes through the face of the watch, and has an index-hand, J, upon it, with a small dial properly divided off, so as to show how 40 much movement is given the indicator J.

The operation will then be as follows: If the rate of speed at which the watch is running is to be altered, it is done from the face, without opening the back part of the watch, 45 by simply moving the indicator J. This turns the shaft and the gear-wheel I, which imparts motion to the pinion H and through its shaft to the pinion G. The latter pinion moves the rack E, which is fixed to the end of the regulator-arm, and thus makes the desired change.

Having thus described my invention, what I claim as new, and desire to secure by Letters Patent, is—

1. The regulator-arm D, having the curved 55 rack E at its outer end, in combination with the pinions G and H, fixed to opposite ends of a shaft, the gear-wheel I, and index J, substantially as herein described.

2. The means for regulating a watch without opening or exposing the interior, consisting of the indicator J, movable over a scale upon the watch-face and connected with a curved toothed rack, E, upon the regulator-arm by means of the intermediate pinions and 65 shaft, substantially as herein described.

In witness whereof I hereunto set my hand.

JULIUS C. LANDMANN.
